UNITED STATES PATENT OFFICE.

ALANSON CARY, OF NEW YORK, N. Y.

DOOR OR OTHER MAT.

SPECIFICATION forming part of Letters Patent No. 388,826, dated September 4, 1888.

Application filed November 5, 1887. Serial No. 254,361. (No model.)

To all whom it may concern:

Be it known that I, ALANSON CARY, of the city, county, and State of New York, have invented a new and useful Improvement in Door 5 or other Mats, of which the following is a full, clear, and exact description.

This invention relates to mats placed at doors, in halls, and elsewhere, which are of an open-work construction and which are usually 10 made of metal, and present a hard or harsh and scraper-like rubbing-surface for the more effectual removal of mud and dirt from the boots or shoes of pedestrians.

The invention consists in the construction 15 and combination of parts, substantially as hereinafter described, and pointed out in the claims.

Reference is to be had to the accompanying drawings, forming a part of this specification, in which similar letters of reference indicate 20 corresponding parts in all the figures.

Figure 1 represents a top or plan view of a mat embodying my invention and side views of longitudinal and end strips used in the construction of the frame of the mat. Fig. 2 is a 25 transverse section upon the line $x x$, Fig. 1. Fig. 3 is a view in perspective of one of the corrugated strips or bands detached.

A and B indicate the side and end strips of which the frame of the mat is composed. A 30 convenient mode of uniting these strips, which, as well as the other parts of the mat, I usually make of metal, is to construct them respectively with tongues $a a$ and slots $b b$ at or near their ends, and then, or after arranging said strips 35 with their longitudinal edges uppermost and undermost, to partly bend said tongues, so that they will enter the slots from their outside, and subsequently to further bend them, so that they will lap over or upon the inner faces of 40 the strips or plates with which they engage, as clearly shown in Fig. 1. This is a strong and easy manner of putting the frame together.

C C are the corrugated strips which form the rubbing or wiping surfaces of the mat. 45 These strips are narrow flat ones, corrugated on their faces in direction of their length, and when arranged within the frame A B are placed with their longitudinal edges uppermost and undermost. Like the frame plates 50 or strips, these strips or plates C are also made with tongues $e e$ at their ends, which are en-

tered through slots $d d$ in the frame-strips B and afterward bent over on the outside to effect their lock and engagement with the frame. In this way or by these means both the frame 55 and its corrugated wiping strips, which latter extend along or across the frame within it, and of which there may be any number arranged at suitable distances apart, are simply and securely put together without the aid of rivets 60 or bolts, although, if desired, the outer corrugated strips may be united with the frame-strips A A by rivets l where meeting the same. The strips C are of the same depth, or there-about, as the frame strips, and are constructed 65 on their upper and lower edges with notches $f f$, to receive within them, so as not to project outside of the upper and lower surfaces of the mat, a series of cross binding or tying wires, g , each of which is doubled lengthwise, and its 70 doubled end h , which lies in notches k in the upper and under edges of one of the side frame-plates, A, arranged on the outside of said plate, while the free portions or two lengths of the doubled wire are woven or crossed alternately 75 above and below the corrugated strips C within the notches $f f$ and their outer ends passed through a slot, j , in the opposite frame-plate A and clinched on the outside thereof by bending over said ends in reverse directions. These 80 wires g , thus applied, serve to bind or tie the sides of the frame together and the corrugated strips C, at different points in their length, with each other, and to generally stiffen the mat and prevent the corrugated strips from spreading 85 when being wiped upon by the feet, and, secured as described, they further provide for putting the whole mat together without rivets or bolts.

The wiping or rubbing strips C, by reason 90 of their corrugated construction, not only provide for an extended wiping edge or surface, and this in an angular or gradual manner, which will facilitate the removal of the dirt from the boot or shoe sole, but they give an extended and waved base which will most materially serve to keep them in their upright position when the boot or shoe is rubbed over them.

The mat thus formed is largely self-cleaning 95 and the corrugated strips may yield freely under pressure, thus preventing the dirt from

firmly adhering. Then, again, as the corrugated strips are parallel they do not form substantially diamond-shaped openings between them, the angles of which would cause dirt to collect, and in such a construction the strips could not have a free yielding movement, as in my construction.

Having thus described my invention, what I claim as new, and desire to secure by Letters 10 Patent, is—

1. A mat comprising a series of connected corrugated parallel flexible strips set edgewise, with their convex portions facing the concave portions of the adjacent strips, substantially 15 as set forth.

2. A mat comprising a series of parallel corrugated strips set edgewise and wires uniting said strips between their ends, substantially as set forth.

20 3. A mat comprising the frame formed of end and side strips provided with tongues and apertures, the tongues of one strip overlapping the outer end of the adjacent strip and passing inward through the aperture therein and

against the inner face thereof, and the scraping strips secured within the frame, substantially as set forth. 25

4. The herein-described mat, comprising the frame, the end bars of which are apertured and the side bars notched in their upper and lower edges, the parallel corrugated strips notched in their upper and lower edges in line with the notches in the frame and formed with tongues on their ends passing through the apertures in the ends of the frame, and the 30 binding wires crossing said strips and side bars through said notches, substantially as set forth. 35

5. In a mat of the character described, the wiper-strip formed of a strip of sheet metal 40 corrugated flatwise and provided with notches in its upper and lower edges and with tongues or tenons at its ends, substantially as set forth.

ALANSON CARY.
